SPOOL TRUCK FOR SCREEN PRINTING APPARATUS

Harry Fleisher, Watertown, Conn., and George H. Tillett, Jackson Heights, N. Y., assignors to Roto-Matic Screen Printer, Ltd., New York, N. Y., a corporation of New York

Application September 6, 1941, Serial No. 409,868

2 Claims. (Cl. 101—114)

This invention relates to apparatus for applying designs upon flexible webs of textile fabrics, paper, and like materials, and more particularly to an improved apparatus employing a stencil-printing screen.

This invention is an improvement over a screen printing apparatus disclosed in a prior Patent No. 2,210,474 issued August 6, 1940, to George H. Tillett, entitled "Color printing web."

This application is a continuation in part of our prior application, Serial No. 364,604, filed November 7, 1940, entitled "Screen printing apparatus."

One object of this invention is to provide means to secure a web-carrying spool, mounted on a movable carrying truck, in accurate alignment with the screen printing apparatus, whereby the area of web to be printed will be in proper transverse registry with the stencil screen.

Another object of this invention is to provide an improved apparatus for applying designs upon flexible webs of the above nature, which will be relatively inexpensive to manufacture, simple in construction, easy to operate by relatively unskilled labor, compact, ornamental in appearance, and very efficient and durable in use.

With these and other objects in view, which will appear as the description proceeds, there have been illustrated in the accompanying drawings several forms in which the invention may be conveniently embodied in practice.

Briefly, the screen printing apparatus of this invention includes a central table for supporting a screen frame and a pair of spools, one carrying a roll of web to be printed, and the other serving as a take-up roll for the web after printing. The web to be printed is adhesively fixed to a carrier belt which is fed manually intermittently from one spool below the screen to be wound upon the other spool. Provision is also made of marginal spacer strips secured to the carrier belt so that when said belt is wound in spiral condition, the color paste freshly printed upon the web will be kept out of contact with the adjacent layer of said web, whereby smudging of said color will be prevented, and said fresh color will be given a chance to dry. The spacer strips also serve to separate the successive layers of the web and provide between them a drying space through which a stream of dry air may be forced.

By winding the printed web in spiral form upon the take-up spools, the material may be stored while drying or curing in the minimum of space as compared to the former methods of drying printed webs on elongated flat tables or suspend-

ing said webs in festoons or loops. The compact coiled web-carrying spools of the present invention are movably mounted on caster trucks so as to facilitate the feeding of the web back again through the printing apparatus for applying additional colors or printing the web at different areas from those originally printed.

In the drawings:

Figure 1 is a front elevational view of the improved screen printing apparatus embodying the invention.

Figure 2 is a broken end elevational view of the same.

Figure 3 is an enlarged and broken transverse section taken on the line 3—3 of Figure 2 and shows a top plan view of the spool truck aligning and clamping means.

Figure 4 is a side view of the parts shown in Figure 3.

Figure 5 is a broken top view of one corner of the spool truck and machine frame shown in unclamped and partly separated position.

Figure 6 is a perspective view of a spool truck with a spool mounted thereon.

Figure 7 is a broken sectional view of an assembled spool and truck with a modified form of clamp mechanism for detachably connecting them together.

Figure 8 is a side view of the same.

Referring now to the drawings wherein like reference numerals designate like parts throughout the several views, the numeral 10 denotes a flat table top which, in this instance, is suitably supported by four corner uprights, or legs, 11, 12, 13, and 14. The front uprights 11 and 12 are connected and braced by horizontal bars 15, 16, and 17 while the rear uprights 13 and 14 are likewise connected and braced by similar horizontal bars located behind said bars 15, 16, and 17, and concealed thereby as viewed in Figure 1. The front uprights 11 and 12 are connected and braced at the top by horizontal side bars 18, 19, and 20, and the uprights 11 and 14 are braced by similar side bars concealed thereby. At each end of the apparatus, provision is made of upright bars 21 extending from the lower horizontal bar 15 to the upper bar 17, and a short vertical bar 22 extends at each side from the intermediate horizontal bar 19 to the lower bar 20 (Figure 2).

Provision is also made of a pair of horizontal shafts 23 mounted in and extending between the front uprights 11 and 12, and the rear uprights 14 and 13, respectively. Each of said shafts 23 is journaled at each upright 11, 12, 13, and 14,

in brackets 24 (Figures 1 and 2), each of which is vertically adjustable in and is secured to the respective upright by a bolt 25 passing through an elongated slot 26 provided in the bracket 24 and screw-threaded into the respective upright. A hand wheel 27 is secured on the front end of each shaft 23 and a sprocket 28 is secured upon the rear end of said shaft. The shafts 23 are extended at their front ends 29 beyond the uprights 11 and 12, and said ends are preferably made hexagonal in cross-section to removably receive a manually-operated crank handle 30.

The table top 10 extends rearwardly beyond the corner uprights 11 and 14, as at 31, and is provided with a pair of transversely-spaced apart bearing brackets 32 and 33 adjustably mounted thereon by means of bolts 34 and 35 passing through a common elongated slot 36 in each bracket and through the table top extension 31, (Figures 1 and 2). An angle piece 37 secured to the table top extension 31 has a screw 38 threaded therethrough into engagement with each of the brackets 32 and 33 to permit them to be held in any desired position and to prevent said brackets from moving rearwardly when the machine is being operated.

Stencil screen

Provision is also made of a swingable stencil-supporting frame, (Figures 1 and 2), comprising end rods 39 and 40, and side bars 41 and 42—the rear end rod 40 being pivoted in bearings carried by the brackets 32 and 33, respectively. The rods 39, 40, 41, and 42 are connected together at the corners of the stencil frame by four angle blocks 45, thus maintaining the frame in rectangular shape.

Four vertically disposed posts 46 extend upwardly—one from each angle block 45—to support side rods or tracks 47 and 48 which are spaced above the side rods 41 and 42, respectively, and are parallel thereto. An elongated angle bar 49 extends between the side rods 41 and 42 adjacent the front end of the screen supporting frame, and a similar angle bar 50 extends between the rods 41 and 42 adjacent the rear ends thereof. The angle bars 49 and 50 are adjustably secured to the respective rods 41 and 42 by clamping brackets 51, and are arranged to have one of their angle portions horizontal and the other vertical. By means of the brackets 51, the angle bars 49 and 50 may be adjusted longitudinally in the direction of web travel along the rods 41 and 42 to position the stencil frame supported thereby in the desired location.

The horizontal base portions 52 of the angle bars 49 and 50 extend toward each other and form opposing seats for a rectangular stencil screen, which, in this instance, is made of four narrow wooden strips 53, 54, 55, and 56, and secured together at their adjoining ends. A printing stencil sheet 57 is stretched across the bottom of the stencil screen, said sheet 57 being preferably made of specially treated silk having the desired perforated design formed thereon through which the thin color paste may penetrate and be applied by a squeegee to the web W placed thereunder. In this instance, the front and rear strips 53 and 54 of the stencil screen are removably seated on the horizontal portions 52 of the angle bars 49 and 50 of the swingable stencil screen supporting frame.

The stencil frame, comprising the strips 53, 54, 55, and 56 is seated in the carrying frame, comprising the bars 39, 40, 41 and 42, and may

5 be brought into exact register with the design on the stencil screen by adjustment of the vertical limit arm 58, (see Figure 2), of an adjustable guide bar having a horizontal arm 59 which is secured to the table top 10.

6 The stencil screen, 53, 54, 55, and 56 may be manually-lifted from the underlying web W whenever it is desired to shift the web by swinging its carrying frame 39, 40, 41, and 42 upwardly 10 about the hinged connection of the rods 40 in the bearings 43 and 44 as a pivot.

15 Provision is also made of means to manually lift the stencil screen carrying frame 39, 40, 41, and 42, and such means comprises a pivoted foot treadle 80 which, as shown in Figure 2, is connected to the front rod 39 of the screen carrying frame through a system of links and levers arranged with a "mechanical disadvantage" whereby a comparatively small movement of the treadle 20 80 will move said frame a relatively large amount.

25 The foot treadle 80 is pivoted to a cross bar 82 extending between the lower side bars 20, and provision is made of a short upstanding link 83, which loosely connects the forward part of the 25 treadle 80 with a long vertical link 84. The upper end of the long link 84 is loosely connected to a short vertical link 85, which in turn is pivoted to an inclined arm 86 at a point closely adjacent the lower fixed end 87 thereof. The end 30 87 of the arm 86 is pivoted to the front intermediate upright 21 between a pair of angle blocks and the upper end 88 of the arm 86 is connected by a chain, 91 (see Figure 2), reeved over a pulley 92, supported on the rear surface of the upright 35 21, said chain passing downwardly from said pulley and being connected to a post 93 secured to a vertical slide 94, which is adapted to loosely embrace the upright 21.

40 The slide 94 is connected to the lower end of an upstanding plate 95 (Figures 1 and 2), which carries a short horizontal shaft 96 at its upper end. The shaft 96 extends beyond the sides of the plate 95 and has rollers 97 journaled on each end thereof. The rollers 97 engage blocks 98 secured to the underside of the front screen frame rod 39 and serve to reduce friction. By means 45 of this construction, it will be seen that, when the operator steps on the treadle 80, force will be transmitted through the links 83, 84, 85, and 86, chain 91, slide 94, plate 95, to the rollers 97, causing the front end of the stencil screen carrying frame to swing upwardly and lift the stencil screen out of contact with the web W. To assist the operator in this operation, counter-weights 99 may be hung upon the arm 86 adjacent its upper end 88. The stencil carrying frame is engaged at its forward end by a pair of curved strips 154 and 155 (see Figures 1 and 2) which serve to guide the angle blocks 45 as this frame is lowered into place.

55 The web W is adapted to be fed across the table top 10 under the stencil screen 57 from one side of the printing apparatus to the other. In order to avoid any stretching or movement of the web W, it is temporarily secured upon a carrier band, or belt, 100, preferably constructed of heavy flexible paper, by means of a non-drying, sticky adhesive which may be composed, for example, of a mixture of China clay and glycerine. By the use of this adhesive, the carrier belt 100 may be used repeatedly before replacement is necessary, due to the fact that it may be stripped therefrom without damage to the belt 100 of the web W. In most instances, only the

outer fibres at the undersurface of the W are impregnated by the adhesive.

Provision is also made of a pair of spacer strips 101 and 102 disposed beneath both margins of the carrier belt 100, and preferably cemented thereto, (see Figure 7). It will be understood that said strips 101 and 102 may, if desired, be riveted to the carrier belt 100 as by eyelets, within the scope of the invention. The combined web W, carrier belt 100, and spacer strips 101 and 102, are adapted to be guided across the table top 10, by means of a pair of transverse grooves 103 and 104 respectively, formed in the upper surface of said table top 10, (see Figure 2). When the web W and the carrier strip 100 are wound into a spiral coil upon a spool 105, (as shown in Figures 1 and 2), it will be understood that the belt 100 will be spaced apart in successive layers by the strips 101 and 102 at its edge, thus providing an air space therebetween, protecting the color paste printed on the web W and preventing "smudging" of the table top 10 thereby. The color will thus be permitted to penetrate uniformly into the web and produce a sharp and distinct reproduction of the design thereon. The edges of the web carrier belt 100 outside the web are preferably coated with shellac or other suitable material to seal them against moisture and afford additional stiffening.

The color paste employed in the screen printing apparatus is adapted to be forced through perforations in the stencil screen 57 onto and into the web W by means of a squeegee blade 106, preferably made of soft rubber and having its upper edge set into a recessed strip 107. The strip 107 is hinged as at 108 to another strip 109, located above it, which strip 109 is adapted to be clamped between a pair of transverse angle bars 110 and 111 by a pair of thumb screws 112. The angle bars 110 and 111 are secured to the forward ends of a pair of short horizontal slide members 113 and 114 of inverted U-shape cross-section. The legs of each inverted U-shaped member straddle the parallel side tracks 47 and 48 and thus guide the squeegee blade 106 in its manual reciprocation by the operator who grasps a relatively long handle rod 115 secured at one end to the cross bars 110 and 111, as shown in Figures 1 and 2. It will be noted that the inverted U-shaped guiding members 113 and 114 do not actually rest on the tracks 47 and 48, but the weight of this structure and the squeegee blade 106 is imposed directly upon the stencil screen 57 so as to cause the color paste to pass therethrough and upon the web beneath it. The pressure of the squeegee blade 106 upon the screen may be increased if desired by the use of suitable ring shaped weights 116 surrounding a pair of vertical posts 117 extending upwardly from the guide members 114.

In operation, the squeegee blade 106 will be lifted at each end of its stroke and moved and lowered at the opposite side of the mass of color paste so as to push it in the reverse direction. This operation is readily accomplished by swinging the handle rod 115 upwardly and causing the rear ends 119 and 120 of the guide members 113 and 114 to engage the tracks 47 and 48 which act as fulcrums therefor.

When the printing operation is completed, the squeegee blade 106 will be raised away from the stencil screen 57 and maintained in such raised position, while the stencil screen is also lifted and the web shifted to bring a new unprinted portion into registry with the screen. For this purpose,

provision is made of a pair of transversely spaced apart standards 121 and 122 secured to the table top 10 at the rear of the stencil screen supporting angle bar 50. Each of the standards 121 and 122 has a horizontal rearwardly extending arm 123, 124, and forwardly extending angle arm 125, 126, respectively. The arms 123 and 124 extend outwardly in opposite directions and carry rollers 127, and the arms 125 and 126 extend inwardly toward each other and carry rollers 128. When it is desired to support the squeegee blade 106 up out of contact with the stencil screen 57 at the rear end of its stroke, it will merely be necessary to tilt the handle 115 upwardly to cause the rear ends 119 and 120 of the guide members 113 and 114 to be disposed under the rollers 127, and the rear cross bar 111 to be disposed above the rollers 128. The web-carrying belt with the web W adhering thereto may then be fed across the table top 10 from the feed spool 105 on one side of the printing apparatus to the take-up spool 105 on the other side. Each of the spools 105 has a hollow shaft 129 extending from its rear end, and has a sprocket 130 detachably secured to said extending end by a set screw 131. A chain 132 is reeved over the sprocket 130 and the sprocket 28 on the hand wheel shaft 23, whereby rotation of the hand wheel 27 on the take-up side of the apparatus will cause the web W to be fed across the table top 10 from the feed spool 105.

In order to insure accurate printing, indicating lines are marked at spaced intervals along the edge of the carrier belt 100, and a single line is marked on the table top 10. These marks when in alignment indicate to the operator that the web W has been properly positioned in accurate registration for another printing operation.

Spools

As herein shown, a pair of identical spools 105 are provided, which may be selectively used for "feeding" and "taking-up" of the web. Each spool is permanently mounted upon a truck 135 having casters 136 whereby it may be wheeled toward and away from the apparatus to carry the web into and out of printing position. In order to insure accurate registration of the printed designs on the web, means are herein provided on each side of the printing apparatus for alining the spool carrying truck 135 with said apparatus. The alining means above referred to includes two pairs of resilient arms 131, 137a extending outwardly from the side end uprights 12, 13, and 11, 14. The arms 131, 137a are each curved outwardly to facilitate the movement of the side base bars 138 and 139 of the truck 135 into engagement therewith and to guide the feeding spool so that the web W to be printed will be in correct transverse registry with the stencil screen when it is fed into printing position.

In order to lock the spool truck 135 in operating position, provision is made on each of said alining means of a toggle mechanism comprising a lever 140 having one end pivoted as at 141 to the adjacent resilient arm 131, 137a. A handle 142 at the other end of the lever 140 is provided to manipulate the same. Provision is also made of a thin rod 143 having a hooked end 144 adapted to catch into elongated slots 145 provided in the side base bars 138 and 139 and pivotally secured to the lever 140 intermediate its ends, said rod 143 passing through a vertical post 146 which is arranged to rotate in the lever 140. 75 A coiled spring 147 surrounds the rod 143 and

reacts between the post 146 and a washer held on the outer end of the rod 143 by lock nuts 149 and 150. When it is desired to hold the truck in the locked position (as shown in Figure 3), the hooked end 144 of the rod 143 will be connected to the truck side bars 138 and 139 by engagement in the slot 145 nearest thereto and the levers 140 will be swung from the open position, shown in Figure 5, into the truck-locking position as shown in Figure 3. If desired, an additional slot 145 may be used so that the trucks may be readily reversed and either side thereof selectively applied to the printing apparatus.

Web-drying apparatus

While the apparatus is being operated, and a freshly printed web W is being wound continually upon the take-up spool 105, a constant flow of dry air will be directed against the surface of the web on said spool by means of a duct 151 leading from a central motor driven air blower 152 (see Figure 1). Additional drying may also be obtained by means of an auxiliary blower, not shown, to force dry air into the hollow spool shaft 129, which air will be caused to flow outwardly through perforations 153 therein and between the layers of the spiral coil of web W wound thereon.

As is clearly shown in Figures 1, 3, 4, and 6, the side base bars 138 and 139 of the spool carrying truck 135 are joined together by front and rear base bars 156 and 157. Moreover, a pair of vertical brackets 158 and 159 of trapezoidal shape extend upwardly from the side bars 138 and 139 of the truck and have journal blocks 160 mounted upon the upper edge of each of said brackets 158 and 159 to support the ends of the shaft 129 of the spool.

Provision is also made of a pair of collars 161 and 162 secured on the shaft 129 by set screws 163 whereby the spool may be held in any desired lengthwise adjusted position with respect to the truck and to thus permit alignment of the flanges 164 and 165 of the spool with the web-carrying strip 100. The flanges 164 and 165 are secured to the spool shaft by circular ribbed plates 166 and 167, respectively.

In the modified form of the invention, shown in Figures 7 and 8, a novel clamping mechanism is disclosed for detachably connecting the truck 135 to the central screen printing table. This mechanism comprises a pair of levers 170, 170 on each end of the table pivoted to the legs 12 and 13 by horizontal bolts 171, 171, said levers having down-turned catch hooks 172, 172 for engagement with the bases of triangular wedge-shaped lugs 173 secured to the extremities of the base bars 138, 139, respectively, of the spool truck 135.

The opposite ends of the levers 170 are provided with rectangular pedals 174, 174, and said levers are also provided with vertical cross bars 175, 175, having eyes 176 at their upper ends for connection to one end of inclined coiled springs 177, the other ends of said springs being attached at eyes 178 formed in the legs 12 and 13 of the printing table, so as to cause said spring to exert a continuous tension upon said lever tending to urge it towards the position shown in Figure 8. The opposite ends of the cross bars 175 are provided with horizontal stop ears 179 which prevent the levers 170 from swinging beyond the position shown in Figure 8.

Provision is also made of a pair of fixed outwardly resilient curved guide strips 180 and 181 secured to the printing table below the levers 170

which serve to guide the base bars 138, 139 and facilitate the insertion of the spool truck into its proper aligned position with respect to the central printing table.

5 By means of this construction it will be seen that the spool truck may readily be released from the printing table by first depressing either of the pedals 174 and pulling that side of the truck outwardly away from said table. The truck may then easily be rolled out from engagement with the printing table.

If desired, rubber bumpers 182 may be attached to the end base bars 12 and 13 of the table to absorb the shock when the truck is 15 forcibly engaged with the printing table.

Operation

The operation of the above described screen printing apparatus is substantially in accordance 20 with that disclosed in the above-mentioned Patent No. 2,210,474. In brief, the operation is as follows:

Assuming the squeegee blade 106 is held in raised position by the rollers 127 and 128 (see 25 Figure 5), the stencil screen frame will be swung upwardly by depressing the treadle 80. The web-carrying belt 100 will then be drawn across the table top 10 from the feeding spool 105 with the spacer strips 101 and 102 guided by the grooves 30 103 and 104, respectively. The free ends of the web-carrying belt 100 will then be attached to a take-up roll 105, which has first been locked in place at the other side of the printing apparatus. The hand wheels 27 will then be turned 35 to bring the first mark on the carrier belt into alignment with the mark on the table top 10, whereupon the stencil screen holding frame will be lowered to cause said screen to engage the web W. The squeegee blade 106 will then be lowered upon the rear end of the stencil screen 40 57 and the proper quantity of color paste will be then placed upon the screen 57 in front of the blade 106, which may then be pulled forwardly by means of the handle 115.

45 When the squeegee blade 106 is in its forward position after having traversed the length of the screen 57, it will be lifted by tilting the handle 115 upwardly and placed in front of the mass of color paste, and then pushed rearwardly to 50 spread the same along the screen 57. After the desired number of strokes of the squeegee blade 106 have been made, said blade will be latched in its raised position as above described. The stencil carrying frame will be swung upwardly 55 by means of the treadle 80. The web W will then be fed along, the desired amount, to bring the next desired indicating mark on the web-carrying belt into registry with the mark on the table top 10. This procedure will be continued 60 until the web has been completely unrolled from the feed spool and wound up on the take-up spool.

After the spool of unstenciled web has been 65 unwound from the feeding spool, printed, and wound up on the take-up spool, the latter may be unlocked and rolled away from the printing apparatus for drying or other treatment. It will then be returned to the printing apparatus on either side thereof, and the previous take-up 70 roll will then serve as the feed roll—it being merely necessary to shift the crank handle 30 to the other shaft 23 to operate the feeding mechanism and take-up mechanism, as described above.

While there have been disclosed in this specifi-

cation several forms in which the invention may be embodied, it is to be understood that these forms are shown for the purpose of illustration only, and that the invention is not to be limited to the specific disclosures, but may be modified and embodied in various other forms without departing from its spirit. In short, the invention includes all the modifications and embodiments coming within the scope of the following claims.

Having thus fully described the invention, what is claimed as new and for which it is desired to secure Letters Patent, is:

1. In a latch mechanism for holding a web-carrying spool in accurate registry with a screen printing table, a resilient outwardly curved arm

10

15

connected to said table and having guiding engagement with a movable truck upon which said spool is mounted, a toggle lever connected at one end to the free end of said resilient arm, and an elongated rod slidably connected to the intermediate portion of said toggle lever, and having selective engagement with any one of a plurality of slots in the base of said truck frame.

2. A latch mechanism as defined in claim 1 in which said rod is spring-pressed to cause said lever to resist the movement of said toggle lever from either open or closed positions.

HARRY FLEISHER.
GEORGE H. TILLETT.
